(Cl. D58—8)

FIG. 2.

FIG. 1.

FIG. 3.

FIG. 1 is a side elevational view of a bottle embodying my new design;

FIG. 2 is a top plan view thereof; and

FIG. 3 is a bottom plan view thereof.

The side not shown is the same as the side shown.

The essential feature of my design resides in the inverted conical upper portion of the bottle disclosed having narrow grooves defining wide flat bands, as shown.

I claim:

The ornamental design for a bottle, substantially as shown and described.
